[57] CLAIM

The ornamental design for a display stand, as shown and described.

DESCRIPTION

FIG. 1 is a perspective view of a first embodiment of the display stand;

FIG. 2 is a top plan view thereof;

FIG. 3 is a bottom plan view thereof;

FIG. 4 is a front elevational view thereof;

FIG. 5 is a side elevational view thereof;

FIG. 6 is a perspective view of a second embodiment of the display stand; and,

FIG. 7 is a perspective view thereof from the opposite side; The top plan view and the bottom plan view of the second embodiment are disclosed in FIG. 2 and FIG. 3 respectively.
